(57) CLAIM

I claim the ornamental design for a post skirt, as shown and described.

DESCRIPTION

FIG. 1 is a perspective view of the post skirt embodying the design of the present invention.

FIG. 2 is a top plan view thereof;

FIG. 3 is a side elevational view thereof; and,

FIG. 4 is a perspective view, showing the post skirt in use. The broken line showing of environment is for illustrative purposes only and forms no part of the claimed design.

1 Claim, 3 Drawing Sheets

FIG.1.

FIG. 3.

FIG 2.

FIG. 4.
